UNITED STATES PATENT OFFICE

149,712

DESIGN FOR AN ELECTRIC SWITCH HANDLE

William G. Waggoner, Stamford, Conn., and Roger B. Kerr, Jamestown, R. I., assignors, by mesne assignments, to The Trumbull Electric Manufacturing Company, a corporation of Connecticut

Application April 17, 1947, Serial No. 138,452

Term of patent 14 years

(Cl. D26—1)

To all whom it may concern:

Be it known that we, William G. Waggoner and Roger B. Kerr, citizens of the United States, residing respectively at Stamford, in the county of Fairfield, State of Connecticut, and Jamestown, in the county of Newport, State of Rhode Island, have invented a new, original, and ornamental Design for an Electric Switch Handle, of which the following is a specification, reference being had to the accompanying drawing, forming a part thereof.

In the drawing showing our new design for an electric switch handle, Fig. 1 is a side elevation; Fig. 2 is a plan view, and Fig. 3 is an elevation of the right end of the handle as shown in Figs. 1 and 2.

We claim:

The ornamental design for an electric switch handle, as shown.

WILLIAM G. WAGGONER.
ROGER B. KERR.
